Gilbert Warner & Robert Petition. Canajoharie N.Y.
G. Warner

The Scheme expressed in these Letters Patent and Making part of the same containing a description in the names of the said Gilbert Warner & Robert Petition & their Assignee Agreement No. 2. Machine for forming and stretching Collars. Letters

To all to whom these presents shall come, Gilebert Warner & Robert Petition of Canajoharie in the County of Montgomery State of New York have invented a new and useful improvement in a machine used for forming and stretching Collars used around the neck of Hoses and other vessels for drawing, to wit that the following is a full and exact description of the construction and operation of the said Machine as invented as improved by us.

The following is a full description of this Machine which is made out of plank and is ten inches thick and fourteen inches wide and twenty six inches long which bottom rest upon four legs fastened into the bottom upon this bottom is placed and fastened a combination of several pieces of timber which will together form the shape of the inside of a collar when finished and upon which the collar is to be formed and stretched as hereinafter mentioned.

This combination of timber consists of four pieces, and are as following. First the piece that forms the lower part of the collar is about fifteen inches wide and four feet high and about five inches thick being bounded on one of the sides forming the rim, which is a circular form to form and stretch the lower part of a collar which said piece of timber is fastened down with two or more screws with nutts underneath the bottom as aforesaid. The second piece of the combination of timber is four feet wide by five inches thick and eight inches wide at the widest end.

This is then narrowed down to the shape of a wedge by timber towards the other end at which place it is only five inches wide & a shoulder or projection formed by the narrower end of the said piece of timber and which said shoulder end is deformed and caused out to form and stretch the upper end part of the sides of a collar. And said piece of timber

upon the bottom of the machine excepting the two backards
represented by a small piece of timber fastened at the lower part and at the middle
so as to form the upper part of the collar which said small piece of timber is to
go through the bottom of the machine and, turning backwards and forwards as tenons
are mentioned. The wide end of said piece of timber is to go over the middle of the frame
and of said widest piece of the said piece of timber described.

The two remaining pieces of timber are formed
alike in every particular and when in order operate in the same way. They are
each twelve inches long and three and a half inches thick at the lower end and
nearly high when placed on the bottom of the machine in their proper places and
standing nearly from the center each way and, also, crossed out to form, and make
the part of a collar between the upper and lower part of it and are placed upon the
stiles and against the shoulder of projection of the second piece of timber described
and extending the inches along the ends of the first piece of timber to which said
four pieces of timber adjoin and placed and fastened upon the bottom part
of the machine as aforesaid from the shape of the inside of a collar which is
lined. And said combination of timber when placed and fastened upon the
bottom of the machine as aforesaid are sixteen long on the top and ten and
a half wide at the top but may be enlarged by the turning of a screw as here
and after mentioned to a collar of the size of thirty four inches long and thirty
two inches wide. That part of the combination of timber which goes over
and stretches a collar within the collar which is to be covered with a cover.

The screw aforesaid is before mentioned
with a crank to it of the same which said screw is placed through the first
piece of timber described forming the lower part of the collar in which is placed
a nut made out of iron to receive the screw and collar that circular part of the
said piece of timber and extends to the wide end of the second piece of timber
described in which there is a plate on which the second screw.

The advantage of the improvement in
the machine are three, that by placing the unformall and unshredded collar
upon the machine as aforesaid and turning the crank aforesaid to the
screw it will effect several different objects by one motion. One of the
said objects is to stretch the collar in length and expand in width

and lastly it will give the collar its proper form & depth, easy on the neck & back of a beast. The manner in which this is done is that by having the collar & jowl, & forward the second piece of timber described in the top and upper part of the collar where the first piece of timber described remains immovable and by the turning of the collar means a head the second piece of timber described is at the same time turned outwards to lay the two side pieces of timber described which stretches the collar in width and in thickness proportioned as it stretches it in length.

At the same time gives all the parts of the collar the proper shape. The two side pieces as described are thrown out by the turning about the second piece described, which it will be necessary to narrow & the shape of a wedge and the side pieces are so placed upon the bottom part of the machine that they can move but one way which is the shape of the collar and are sliding in their proper place by means of cleats which are let in a mark in the bottom piece. In the room of a screw & socket this effect a wedge, may be used by placing and driving it between the first and second pieces of timber described which will move the second piece a head and through the two side pieces out as a forepart.

What we claim as new and improved types is the construction, shape form and combination of the four pieces of timber as described and effect produced in forming and stretching of the collar in length, & width at the same time and with one and the same machine.
